United States Patent Office.

RUFUS HAM AND JOSEPH DURGIN, OF BANGOR, MAINE.

Letters Patent No. 80,823, dated August 11, 1868.

IMPROVEMENT IN DUMPING-CARTS.

The Schedule referred to in these Letters Patent and making part of the same.

TO ALL WHOM IT MAY CONCERN:

Be it known that we, RUFUS HAM and JOSEPH DURGIN, both of Bangor, in the county of Penobscot, and State of Maine, have invented a new and useful Improvement in Tip-Carts; and we do hereby declare that the following is a full, clear, and exact description thereof, which will enable any person skilled in the art to make and use our improvement, reference being had to the accompanying drawings, and to the letters of reference marked thereon.

Figure 1 is a view of our improved tip-cart ready for loading.

Figure 2 is a view of same after discharging a load, showing our improvement.

We construct, of wood or metal, a framework, composed of the stringers A and A', the cross-pieces b, b', and b'', the uprights c and c', and the cross-head piece d.

The cross-pieces b, b', and b'' are secured to the stringers A and A' by raves and bolts, and the uprights c and c' and cross-head piece d are mortised together, and into the stringers A and A', all as shown in the accompanying drawings.

We then construct, of wood or metal, the spindle-headed post E, which is secured and braced by the cross-pieces b, b', and b'', and the plate or circle F, which is supported by and secured to the braces g, g', g'', and g''', all as shown in the accompanying drawings.

We then construct, of wood or metal, the rocker H, and the trundles I, and I', and I''.

The rocker H is secured to the spindle-bolt, in the head of the post E, so as to turn readily upon the same, and is connected to an ordinary cart-body, K, by the hinges j and j', or by some similar contrivance.

The trundles I and I' are secured to the rocker H, and the trundle I'' is secured to the cart-body K, and said trundles I, I', and I'' are so arranged as to play upon the plate or circle F, all as shown in the accompanying drawings.

In operation, the cart-body K is temporarily secured in a horizontal position by the fastenings l and l', as shown in fig. 1, and is loaded in that position.

When the load is to be discharged, the tail-board M is removed, and the fastenings l and l' are disconnected. The cart-body K is then tipped into the position shown in fig. 2, and the load is discharged.

When the load is to be discharged to either side, the fastenings l and l' are disconnected, and the cart-body, with the rocker H, is revolved upon the spindle-headed post E, until in the desired position, the trundles I, I', and I'' travelling upon the plate or circle F, serving to steady and support the load while turning. The tail-board M is then removed, the cart-body K tipped, and the load discharged.

Until the tail-board is removed, the cart-body K may be kept from tipping by passing the hooked end of the rod n (or n', as the case may be,) through the eye-bolt o, or by some similar contrivance.

This frame and cart-body may be permanently mounted upon wheels or runners, as may be desired, or placed upon any ordinary platform railroad-car, platform, cart, or truck for temporary use.

We claim as our invention, and desire to secure by Letters Patent—

The spindle-headed post E and the plate or circle F, in combination with the rocker H and the trundles I, I', and I'', constructed and operating substantially in the manner and for the purposes as shown and described.

RUFUS HAM,
JOSEPH DURGIN.
